UNITED STATES PATENT OFFICE.

WILLIAM E. CRANDALL, OF NEW YORK, N. Y.

ROCKING-HORSE.

SPECIFICATION forming part of Letters Patent No. 326,721, dated September 22, 1885.

Application filed January 24, 1885. (No model.)

To all whom it may concern:

Be it known that I, WILLIAM E. CRANDALL, a resident of New York city, in the county and State of New York, have invented an Improved 5 Rocking-Horse, of which the following is a full, clear, and exact description, reference being made to the accompanying drawings, in which—

Figure 1 is a side view, partly in section, of 10 my improved rocking-horse. Fig. 2 is a cross-section of the same on the line $\alpha\alpha$, Fig. 1. Fig. 3 is a longitudinal section on an enlarged scale of the parts that connect with the spring. Fig. 4 is an enlarged face view, and 15 Fig. 5 an enlarged side view, of the spring-holding clamps.

This invention relates to a new rocking-horse in which a coiled spring is placed directly beneath the center of the rocker to 20 normally hold the horse in the middle position, thereby greatly facilitating the use of the toy.

The invention consists in combining a rocking-horse or rocking toy with a coiled spring, 25 which is placed directly beneath the center of the rocker-frame, and with certain holders for securing thereto the ends of the spring, as hereinafter more fully specified.

In the drawings, the letter A represents a 30 suitable rocking-horse or other contrivance that is placed on rockers B B, which rest on the side rails α of a stationary frame, C. At the middle the two rockers B B are united by a cross-bar, D, beneath which is a cross-bar, E, which unites the two rails α of the stationary frame C.

F is a coiled spring, which is interposed between the two cross-bars D and E and attached to them in manner hereinafter de- 40 scribed, and which, when the parts are in the position shown by full lines in Fig. 1, is in its normal condition—that is to say, the tension of the spring is such as to draw the cross-bar D and hold the same directly over the cross-bar E. When the person on the rocking-horse leans the same forward or backward, as the case may be, the spring F is immediately 45 distended, as indicated by dotted lines in Fig. 1, and being so distended tends to swing the

horse back to its central position, the impetus 50 carrying the rockers over the central position, when the spring is again distended, serving thus to keep the rocker in motion. It will be seen, therefore, that by using the single central spring, when the same is so constructed that it will be distended whenever 55 the horse is rocked, the labor of bringing the horse back to its central position will be almost wholly assumed by the spring and taken off the rider. 60

In Figs. 3, 4, and 5 I have shown in detail the means of securing the ends of the spring F. For this purpose I employ two circular plates, b and d , one for the upper and the other for the lower end of said spring. Each of these 65 plates has on its outer periphery a spiral thread for receiving part of the coiled spring F. This spiral thread is clearly shown at e , in Fig. 5. The plate b is riveted to a plate, f , which in turn is riveted or bolted to the under side of 70 the cross-bar D, and the plate d is riveted to a plate, g , which in turn is bolted or otherwise fastened to the upper side of the cross-bar E. By this connection the ends of the spring are securely held in place, and the plates 75 b d , by engaging the terminal coils of the spring, hold the spring in proper tension, as they prevent it from contracting or expanding longitudinally.

In order to keep the rocker B in position on 80 the frame C, said frame is on its outer sides provided with cheek-pieces h h that flank the sides of the rocker, as shown in Fig. 2, and assist also in preventing the single coiled spring from twisting out of shape. 85

I claim nothing that is shown in Letters Patent Nos. 214,871, 304,205, and 222,898.

I claim—

The combination of the coiled spring F with the spirally-threaded circular plate b , 90 plate f , spirally-threaded circular plate d , plate g , and cross-bars D E, substantially as herein shown and described.

WILLIAM E. CRANDALL.
